UNITED STATES PATENT OFFICE.

MAX D. BARON, OF NEW YORK, N. Y., ASSIGNOR TO WITTEMAN BROTHERS, OF BROOKLYN, NEW YORK, A CORPORATION OF NEW YORK.

METHOD OF MAKING PAPER CONTAINERS.

1,413,251.

Specification of Letters Patent. Patented Apr. 18, 1922.

Application filed November 5, 1920. Serial No. 421,954.

To all whom it may concern:

Be it known that I, MAX D. BARON, a citizen of the United States, residing at New York city, borough of Manhattan, county 5 and State of New York, have invented certain new and useful Methods of Making Paper Containers, of which the following is a specification.

This invention relates to the art of manufacturing containers from paper, and is, more particularly, directed to the method of making tapered paper containers.

The object of the present invention is to provide a method, whereby tapered paper containers may be formed by winding a straight strip of material or web of paper upon a tapered mandrel to the end that a simple, one piece, rigid and durable container body may be formed in an inexpensive and expeditious manner.

In carrying out the present invention, a straight web of paper, to which an adhesive has been applied, is wrapped about a tapered mandrel, but, either before or during 25 the wrapping operation, the strip of paper is conditioned to conform to the surface of the mandrel by causing tucks or folds to be formed in the web for the purpose of compensating for a varying diameter or 30 cross sectional area of the resulting tapered container.

Features of the invention, other than those adverted to, will be apparent from the hereinafter detailed description and claims, 35 when read in conjunction with the accompanying drawings.

The accompanying drawings illustrate one way of practicing the present invention, but the showing therein made is to be understood 40 as illustrative only, and not as defining the limits of the invention.

The drawing illustrates, diagrammatically, the manner in which a straight web of paper may be wound upon a tapered mandrel and 45 tucked or plaited to bring about the shaping of the web to the mandrel.

Referring to the drawings, in which I have diagrammatically illustrated one way of practicing the present invention, A' 50 designates a mandrel, the face of which is shaped in accordance with the desired contour of the finished tapered container. The mandrel A' is tapered as shown and the degree of taper may be greater or less than 55 that illustrated, without in anywise effect-

ing the present invention. Moreover, the mandrel may be of any construction desirable and mounted in any suitable manner for rotation. However, for the purpose of clearly showing the manner in which the 60 paper is wound upon the mandrel, and in order that the outlines of the mandrel may not be confused with the superimposed plies of paper, I have shown the mandrel as cross-hatched.

In practicing the method, a straight web of paper B', substantially equal in width to the desired height of the finished container, is fed to the mandrel and wrapped thereon by any suitable mechanism, but 70 previous to or during the wrapping of the paper web upon the mandrel, said web is plaited or tucked at intervals, to provide tapering tucks, plaits, or folds C', preferably so spaced apart that they will be staggered with respect to one another, or break joints with one another when the strip is wound upon the mandrel. An adhesive is applied to the web, either before it is wound upon the mandrel or after it is wound upon 80 the mandrel, so that the successive plies, as they are superimposed upon one another, will be adhesively secured together. The applying of this adhesive may be accomplished by any suitable mechanism and the successive plies of paper, after they are wound upon the mandrel may be forced into tight engagement with one another by suitable pressure rolls, or other mechanism, forming 85 no part of the present invention.

When a straight web of paper is provided with tapering folds or plaits, as shown, the winding of such a web upon a tapered mandrel, through the application of proper mechanism, results in the conformation of 95 the web to the mandrel in such manner as to compensate for the varying diameter of the mandrel at different points of its length. By properly spacing the plaits or folds C', the successive wraps of paper on the mandrel 100 will result in the breaking or staggering of joints resulting from said folds, and the finished container will embody a wall which is impervious to liquids and moisture. Any desired number of plies may be wrapped 105 upon the mandrel in the manner described, and the number of plies employed will largely depend upon the size of the finished container and the use to which it is to be put. It is found in practice that contain- 110

ers of a size readily adapting them for use as butter tubs, or for analogous purposes, may be constructed in the manner described, the plaits or folds C' serving to impart 5 to the container great rigidity and strength through the reinforcing thereof with the employment of an adhesive as described. The present invention is capable, however, of employment in the manufacturing of smaller 10 or larger containers than butter tubs, and is particularly applicable for use in the manufacture of candy containers, paint cans, or other containers, where rigidity and durability, together with liquid impervious 15 qualities are desirable.

In manner described, a strong, durable and rigid container may be manufactured in a simple, expeditious and economical manner, without the use of dies or machinery 20 requiring nice adjustments. The present invention is thus a marked contrast with the prior practice employed in the manufacture of tapered paper containers and the finished container may be readily made far 25 more serviceable and durable than die cut and formed containers and at but a fraction of the cost.

As a result of the practicing of the method 30 of this invention, as hereinbefore described, the resulting article is a container body to which may be applied any suitable bottom and top closure, the character of which will, of course, greatly depend upon the use to 35 which the container is to be put. In practice, paper bottoms and tops may be applied to the bodies so constructed, or they may be supplied with wooden or metallic bottoms 40 and tops as occasion may require. In view of the fact that the application of a top or bottom to the container involves no part of the present invention, it has not been considered necessary to show and describe the 45 manner in which they may be applied.

In practice, the mandrel A' will be made 50 collapsible, but as this mandrel, per se, forms no part of the present invention, it has not been considered necessary to show in detail the collapsible mandrel and the same has been shown solid for diagrammatic illustration.

In carrying out the present invention, the foregoing illustrative sequence of steps may 55 be slightly varied without departing from the spirit of the invention. In any event, the underlying principle of the invention remains the same, i. e., the linear dimension of at least one edge of the web is changed or 60 varied by overlapping lateral portions of the paper web to bring about the contraction in the linear dimension. For these reasons, the present invention is not to be understood as limited to the specific showings made in the drawing, but is to be construed as is 65 broadly novel as is commensurate with the appended claims.

Having thus fully described the invention, what I claim as new and desire to secure by Letters Patent is:

1. The method of making paper containers which consists in winding a straight web 70 of paper upon a tapered mandrel, and compensating for the taper of the mandrel by forming flat, transverse tapered plaits in the web.

2. The method of making paper containers which consists in winding a straight web 75 of paper upon a tapered mandrel, and compensating for the taper of the mandrel by providing the web with transversely extending flat tapered plaits to change the 80 linear dimension of one edge thereof.

3. The method of making paper containers which consists in winding a straight web 85 of paper upon a tapered mandrel, and compensating for the taper of the mandrel by 90 providing the web with transversely extending flat tapered plaits for a portion of its width to effect a change in the linear dimension of one edge thereof, while the linear dimension of the other edge of the web is maintained constant.

4. The method of making multi ply paper containers which consists in winding a straight web of paper on a tapered mandrel, forming tapering plaits in the web, which 95 plaits extend from one lateral edge thereof and compensate for the taper of the mandrel, and so spacing the plaits from one another longitudinally of the web, that the successive plaits of any one ply will lie intermediate the successive plaits of adjacent plies.

5. The method of making multi ply paper containers which consists in winding a straight web of paper upon a tapered mandrel, 105 providing the web with transversely extending tapered plaits to compensate for the taper of the mandrel and employing the successive plies to maintain the plaits of each preceding ply folded down flat. 110

6. The method of making paper containers which consists in winding a straight strip of paper upon a tapered mandrel, compensating for the taper of the mandrel by forming tapered transversely extending plaits in 115 the web, and folding said plaits down flat.

7. The method of making tapered paper containers which consists in wrapping a straight web of paper upon a tapered mandrel, so as to produce a plurality of superimposed plies in conformity with the surface of the mandrel, and precluding a non-conformity in the winding of the web by effecting a longitudinal variation of a lateral portion of the web, through the introduction 125 thereinto of flat tapered plaits, thereby compensating for the taper of the mandrel.

In testimony whereof, I have signed my name to this specification.

MAX D. BARON.
